UNITED STATES PATENT OFFICE.

DAVID M. STOTT, OF CHICAGO, ILLINOIS, ASSIGNOR OF ONE-HALF TO HORACE E. ARGO, OF CHICAGO, ILLINOIS.

EQUALIZER AND SEPARATOR FOR STEAM.

No. 902,016.

Specification of Letters Patent.

Patented Oct. 27, 1908.

Application filed April 30, 1908. Serial No. 430,056.

To all whom it may concern:

Be it known that I, DAVID M. STOTT, a citizen of the United States, residing at Chicago, in the county of Cook and State of Illinois, 5 have invented a new and useful Equalizer and Separator for Steam, of which the following is a specification.

The objects of my invention are—

1st. To hold back the rushing of the water 10 with the steam out of a steam boiler, which occurs frequently, leaving the boiler empty and allowing it to become super-heated while at the same time there is no steam pressure, as shown by the safety valve. Then when 15 the water returns and comes in contact with the super-heated boiler, it vaporizes so rapidly that the safety valve is unable to take care of it and the result is an explosion.

2nd. To separate the water from the 20 steam before it reaches the main nozzle connecting to the heating system, engine, pump or other device using steam.

3rd. To form a safety device so that if a 25 rush of water should take place it would be stopped until the water level was equalized in the boiler, and at the same time forcing the steam pressure back into the boiler where it would be relieved by the safety valve if too great.

30 4th. To act as a blow-off to remove any oil that may have collected in the boiler, which collecting on the top of same is so detrimental to the making of steam and the proper working of the boiler.

35 This device may be applied either inside, or outside of a boiler, and I do not confine myself to the particular form or arrangement shown in making my claim as it is obvious that this might be modified or changed and 40 still not depart from the spirit of the invention which is when, for any reason the water is inclined to flow out of the boiler with the steam to check the passing of either water or steam from the boiler until an equilibrium is 45 maintained and the water level established.

I attain these objects by the device illustrated in the accompanying drawings of which

Figure 1 shows a side elevation in connection with the ordinary water column and steam gage of a steam boiler with parts broken away to show construction. Fig. 2 is a cross section taken on the line 2—2 Fig. 1. Fig. 3 is a similar view showing the 55 baffle plate lifted up against the cover.

Similar letters refer to the same parts in the several figures.

Let A represent the main body of the device with a flanged opening a at the bottom connected to the supply pipe from the boiler 60 a¹. The body A has a flange a² around the top, bolted to which is the cover A¹, having in its center a flanged opening a³ for connecting with the pipe for conducting the steam wherever it is to do its work. 65

It will be noticed the cover has a portion of its width A² depressed throughout its length for a purpose to be explained later on.

Inside of the chamber A is a baffle plate B which divides the chamber into two parts 1 70 and 2. This plate rests upon flanges or studs b which are formed on the inside walls of the chamber A, along its length, integrally with the side walls. The plate B has openings b¹ 75 b¹ for steam to pass into the chamber 1, so arranged as to direct the steam toward the center of the depressed portion of the cover, along its length. The effect of this is to deflect the steam from its course up through opening a³, allowing any of the water of condensation to fall on the plate B. This plate is formed as a pan to catch this drip and allow it to pass out through one small opening. The end walls of the pan b³ are shaped to fit the depressed portion of the cover at its ends 80 when the plate is raised up as shown in Fig. 3. The sides of the plate are arched along its length forming domes c—c from which the openings b¹ b¹ lead.

The opening b² is sufficient to take care of 90 the little water of condensation which may accumulate in the pan but not sufficient to permit any great volume of water which might rush up with the steam and if not prevented would be forced into the pipes beyond. When such an action occurs the water, coming in contact with the broad surface of the baffle plate B will raise it off the flanges b—b into the position shown in Fig. 3, bringing the holes b¹ b¹ against the curve of the 95 sunken portion of the cover A² closing them completely allowing neither water nor steam to pass further. 100

After the flow is stopped and the pressure directed back into the boiler to be taken care of by the safety valve, the natural tendency of water to seek its level would cause it to flow back into the boiler, either by the pipe D connected with the water column D¹ or through the supply pipe a¹. After the water 110

commenced to return in this way the small opening b^2 in the bottom of plate B would relieve any tendency to form a vacuum in the pipes beyond. The plate B would return to 5 its normal position allowing the steam to pass up the supply pipe through a^3 . The usual steam gage D³ is shown over the top of the water column.

Between the chamber A and the water column D¹ in the pipe D is a valve D³ which when there is oil on the water in the boiler 10 can be opened to draw off the same without emptying the boiler.

Having thus described my invention, what 15 I desire to claim and have granted by Letters Patent is—

1. In a steam separator and water equalizer, a casing provided with inlet and outlet passages, and a baffle plate interposed between said passages in position to be moved by the inrush of water and provided with an opening adapted to be closed by the movement of the baffle plate, due to the inrush of water, and provided with a port suitably positioned to remain open during all movements of the baffle plate, substantially as described.

2. In a steam separator and water equalizer, the combination of a casing provided 30 with inlet and outlet passages, and a baffle plate interposed between said passages and positioned to be lifted by the inrush of water, and provided, near its periphery, with a hole adapted to be closed by the lifting of the baffle plate, and provided, near its center, with a port adapted to remain open during all movements of the baffle plate, substantially as described.

3. In a steam separator and water equalizer, the combination of a casing provided 40 with inlet and outlet passages, and a baffle plate interposed between said passages and adapted to be lifted by the inrush of water, and provided, near its periphery, with a hole 45 adapted to be closed by engagement of the

baffle plate with the wall of the casing when the baffle plate is lifted, and provided with a port adapted to remain open during all movements of the baffle plate, substantially as described.

4. In a steam separator and water equalizer, the combination of a casing provided with inlet and outlet passages, a baffle plate interposed between said passages, and provided, around its periphery, with a backwardly turned edge, and provided, near said edge, with a hole adapted to be closed by engagement of the baffle plate with the wall of the casing when the plate is raised, and provided, near its center, with a port adapted to remain open during all movements of the baffle plate, substantially as described.

5. In a steam separator and water equalizer, the combination of a casing provided with inlet and outlet passages, the wall of the casing adjacent the outlet passage being inwardly dished to provide a boss, and a baffle plate recessed in its center and provided on its edge with a pair of backwardly turned lips or flanges, and having, near its edges, a pair of holes adapted to be closed by engagement of the baffle plate with the boss around the discharge passage, the baffle plate being further provided, near its center, with a hole adapted to remain open during all movements of the baffle plate, substantially as described.

6. In a steam separator and water equalizer, the combination of a casing provided with inlet and outlet passages, and a baffle plate of recessed construction, provided with a port for the passage of steam and the outflow of water of condensation, said baffle plate being adapted to be moved by the inrush of water, substantially as described.

DAVID M. STOTT.
